CIRCUIT BREAKER

William H. Woods, Garden City, Mich., assignor
to Square D Company, Detroit, Mich., a cor-
poration of Michigan

Application October 23, 1952, Serial No. 316,339

10 Claims. (Cl. 200—116)

1

This invention relates to an improvement in circuit breaker construction and more particularly to an improvement in the construction of a trip-free circuit breaker.

An object of the present invention is to provide an improved circuit breaker mechanism which will trip upon the occurrence of an overload within the circuit with which it is associated regardless of whether the switching handle of the circuit breaker is held in the "on" position or released.

Another object of the present invention is to provide an improved circuit breaker mechanism which will have a quick-make and quick-break action when switched to the "on" and "off" positions manually, and a quick-break action when automatically tripped regardless of whether the switching handle of the circuit breaker is held in the "on" position or permitted to move to the tripped position.

Further objects and features of the invention will be readily apparent to those skilled in the art from the specification and appended drawing illustrating certain preferred embodiments in which:

Figure 1 is a side view of the mechanism according to the present invention showing the circuit breaker elements in the "on" position.

Figure 2 is a side view showing the circuit breaker elements in the "off" position.

Figure 3 is a side view showing the circuit breaker elements in the "tripped" position.

Figure 4 is a front view of the present invention along line IV—IV of Figure 2 and with parts broken away.

Referring to the drawing, in which like reference numerals indicate like parts, the circuit breaker of the present invention is mounted within an insulating housing 1. In recesses in the side walls of the insulating housing 1 is supported a cradle member having legs 2 and 3 and crossbars 4 and 5. Also mounted to the insulating housing by means of suitable mounting screws, are conductors 7 and 8. Conductor 7 carries at its inner end a stationary contact 9 and conductor 8 carries at its inner end a bimetal 11.

The legs 2 and 3 of the cradle member are provided with opposed holes which receive a shaft 12 carrying a switching member 13 having an extending toe 14 and strengthening side plates 15 and 16. Extending through the side plates 15 and 16 and the switching member 13 is a shaft 18 upon which is pivotally mounted one end of a toggle link 19. The other end of the toggle link

2

19 extends through a slot in a cross member 21 which is fixedly mounted to legs 22 and 23 of a substantially U-shaped contact carrying member 17 also pivotally mounted on shaft 12. Surrounding the toggle link 19 and seated on the cross member 21 is a toggle spring 24. The member 17 carries a movable contact at 34.

Through additional holes in the legs 2 and 3 of the cradle member is mounted a shaft 25 carrying a U-shaped latching and tripping member 26 having legs 27 and 28 pivoted on the shaft. An integral extension of the latching and tripping member 26 provides a latching tip at 29. Mounted on leg 27 of latching and tripping member 26 is a tripping pin 31. In the leg 22 of the switching member 17 is a cutout portion 30 in which the tripping pin 31 operates. Helical tension spring 32 mounts between the bight of the U of the latching and tripping member 26 and an extension 33 of leg 2 of the cradle member.

The cradle member is held in place in the recesses in the insulating housing 1 when a cover plate 37 and insulating plate 38 are secured to the base by suitable screws (not shown). An operating handle 35 is rigidly connected to the switching member 13 by means of threads on its staff 36.

The operation of the circuit breaker will now be described:

With the circuit breaker in the tripped position, as shown in Figure 3, the toe 14 of the switching member 13 is engaged by the bight of the U of the latching and tripping member 26 and movement of the operating handle 35 in a clockwise direction will lift the latching tip 29 of the tripping and latching member 26 until the free end of the bimetal 11 passes thereunder and holds it in position of Figure 2 against the tension of helical spring 32.

In this normal "off" position of Figure 2, an upward movement of the handle will move the switching member 13 and the side plates 15 and 16 in a counterclockwise direction about shaft 12 to move the shaft 18 until it has passed to the right of the imaginary line between the pivot point of toggle link 19 on the cross member 21 and the center of shaft 12. When shaft 18 has passed this line, the toggle spring 24 will force the cross member 21 to the left and cause the contact carrying member 17 to rotate about its pivot on shaft 12 with a snap action until the movable contact 34 makes contact with the stationary contact 9 as shown in Figure 1. The overcenter action of toggle link 19, toggle spring 24 and cross member 21 will provide continuous

pressure on the contacts when the circuit breaker is closed.

Upon the occurrence of a predetermined overload within the circuit with which the circuit breaker is associated, the free end of the bimetallic strip 11 will flex to the left and will release the latching tip 29. Release of the latching tip 29 will permit the latching and tripping member 26 to rotate about its pivot on shaft 25 under the tension of helical spring 32 and will cause the tripping pin 31 to move in the cutout portion 30 of leg 23 of the contact carrying member 17 until it strikes the right hand edge of the cutout portion when, because the strength of helical spring 32 is greater than that of the toggle spring 24, it will rotate the contact carrying member 17 bodily about its pivot on shaft 12 to open position.

It will be apparent that regardless of whether the switching handle 35 is held in the "on" position or whether it is permitted to move, the release of the latching tip 29 will cause the breaker to trip due to the action of the tripping pin 31 directly on the contact carrying member 17.

If the handle is not held on automatic trip, it will move into the trip indicating position of Figure 3 determined by the engagement toe 14 of switching member 13 with the latching and tripping member 26.

The movement of the parts to manual "off" position is the reverse of the movement to "on" position, toggle spring 24 effecting the movement with a snap action.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. In an automatic electric circuit breaker, a stationary contact, a movable contact cooperating with said stationary contact, an operating handle, overcenter spring means interconnecting said handle and movable contact and operative to effect movement of the movable contact into and out of engagement with the stationary contact as the handle is oscillated, a spring biased trigger, current responsive means normally latching said trigger in inoperative position, and means engageable by said trigger when released by said current responsive means on current overload for effecting movement of said movable contact into disengaged position, said means and trigger operating on current overload to move said movable contact to open position against the bias of said overcenter spring means regardless of the retention of the handle in contacts engaged position.

2. In an automatic electric circuit breaker, a stationary contact, a movable contact cooperating with said stationary contact, an operating handle, overcenter spring means interconnecting said handle and movable contact and operative to effect movement of the movable contact into and out of engagement with the stationary contact as the handle is oscillated, a spring biased trigger, current responsive means normally latching said trigger in inoperative position, and means engageable by said trigger when released by said current responsive means on current overload for effecting movement of said movable contact into disengaged position, said trigger moving said movable contact against the bias of said overcenter spring means regardless of the

retention of the handle in contacts engaged position, means operated by said handle for moving the trigger into an operative position when the handle is moved to contacts disengaged position after an automatic trip, said last mentioned means being engaged upon trigger release to move the handle into a stable intermediate position indicating automatic opening of the circuit breaker.

3. In an automatic electric circuit breaker, a stationary contact, a movable contact cooperating with said stationary contact, a switching arm carrying said movable contact, an operating handle, overcenter spring means interconnecting said operating handle and switching arm, a spring biased trigger, current responsive means normally retaining said trigger in inoperative position, oscillation of said handle moving said overcenter spring means to opposite sides of its dead center position to effect movement of the switching arm to engaged and disengaged positions, release of said trigger by said current responsive means on current overload applying its spring bias to the switching arm independent of the handle to move the same to disengaged position against the bias of said overcenter spring means, the spring bias of the trigger being sufficient to overcome the bias of the overcenter spring means to move the contact arm to disengaged position regardless of the maintaining of the handle in the "on" position.

4. In an automatic electric circuit breaker, a stationary contact, a movable contact cooperating with said stationary contact, a switching arm carrying said movable contact, a pair of toggle links, one of said links having a fixed pivot and the other having a pivotal lost motion connection with the switching arm, spring means biasing said links for breaking on opposite sides of their extended position to effect movement of the switching arm to contacts engaged and disengaged positions, an operating handle for rotating said one link about its fixed pivot to move the linkage through its extended position to effect movement of the switching arm manually at will, a spring biased trigger, a lost motion connection between said trigger and switching arm, current responsive means normally latching said trigger in inoperative position against its bias, said contact arm being freely movable relative to the trigger through said lost motion connection on manual operation, and means engaged by said trigger on its release by said current responsive means on overload to take-up said lost motion connection and effect direct movement of the switching arm into disengaged position against the bias of the toggle spring and regardless of the maintenance of the handle in the "on" position.

5. In an automatic electric circuit breaker, a stationary contact, a movable contact cooperating with said stationary contact, a switching arm carrying said movable contact, a pair of toggle links, one of said links having a fixed pivot and the other having a pivotal lost motion connection with the switching arm, spring means biasing said links for breaking on opposite sides of their extended position to effect movement of the switching arm to contacts engaged and disengaged positions, an operating handle for rotating said one link about its fixed pivot to move the linkage through its extended position to effect movement of the switching arm manually at will, a spring biased trigger, a pin and slot connection between said trigger and switching arm whereby

said switching arm is normally movable relative to the trigger through said pin and slot connection in the manual operation of the breaker, current responsive latching means for said trigger, release of the trigger by said current responsive means engaging the pin and the edge of the slot to effect direct movement of the contact arm by the trigger biasing spring against the bias of the toggle spring and regardless of the maintenance of the handle in the "on" position, and means for effecting reset of said trigger when the handle is moved to "off" position.

6. In an automatic electric circuit breaker, a stationary contact, a movable contact cooperating with said stationary contact, a manual operator, overcenter spring means interconnecting said operator and movable contact for effecting manual movement of the movable contact into and out of its engaged position, a spring biased trigger, a lost motion connection between said trigger and movable contact whereby said movable contact is normally movable free of the trigger in its manual movement to engaged and disengaged positions, current responsive means normally latching said trigger in inoperative position against its bias and operable to release it upon the occurrence of a current overload, and means engaged by said trigger when released by said current responsive means on overload to take up the lost motion connection and move the movable contact into disengaged position against the bias of said overcenter spring means and regardless of the maintenance of the handle in the "on" position.

7. In an automatic electric circuit breaker, a stationary contact, a movable contact cooperating with said stationary contact, a manual operator, a resilient connection between said operator and movable contact biasing the movable contact into engaged position when the operator is in the "on" position, a spring biased trigger, current responsive means normally latching said trigger in inoperative position and operating to release the trigger upon the occurrence of a current overload, said trigger when released moving under its spring bias to move said movable contact to disengaged position against the bias of said resilient connection regardless of the maintenance of the operator in the "on" position, and means for resetting said trigger when the handle is moved to "off" position.

8. In an automatic electric circuit breaker, a stationary contact, a movable contact cooperating with said stationary contact, a manual operator, a resilient connection between said operator and movable contact biasing the movable contact into engaged position when the operator is in the "off" position, a spring biased trigger, current responsive means normally latching said trigger in inoperative position and operating to release the trigger upon the occurrence of a current overload, said trigger when released moving under its spring bias to move said movable contact to disengaged position against the bias of said resilient connection regardless of the maintenance of the operator in the "on" position, and means controlled by said manual operator for returning

the trigger into inoperative position when the operator is moved into "off" position after an automatic operation of the circuit breaker.

9. In an automatic electric circuit breaker, a stationary contact, a movable contact cooperating with said stationary contact, a manual operator, a resilient connection between said operator and movable contact biasing the movable contact into engaged position when the operator is in the "on" position, a spring biased trigger, current responsive means normally latching said trigger in inoperative position and operating to release the trigger upon the occurrence of a current overload, said trigger when released moving under its spring bias to move said movable contact to disengaged position against the bias of said resilient connection regardless of the maintenance of the operator in the "on" position, means controlled by said manual operator for returning the trigger into inoperative position when the operator is moved into "off" position after an automatic operation of the circuit breaker, said last mentioned means being movable by said trigger when released and the operator is not held in "on" position for automatically moving the operator into a position indicating the automatic operation of the circuit breaker.

10. In an automatic electric circuit breaker, a stationary contact, a movable contact cooperating with said stationary contact, a switching arm carrying said movable contact, a pair of toggle links, one of said links having a fixed pivot and the other having a pivotal lost motion connection with the switching arm, spring means biasing said links for breaking on the opposite sides of their extended position to effect movement of the switching arm to contacts engaged and disengaged positions, an operating handle for rotating said one link about its fixed pivot to move the linkage through its extended position to effect movement of the switching arm manually at will, a spring biased trigger, a lost motion connection between said trigger and switching arm, current responsive means normally latching said trigger in inoperative position against its bias, said switching arm being freely movable relative to the trigger through said lost motion connection on manual operation, release of said trigger by said current responsive means on overload effecting a take-up of said lost motion connection and direct movement of the switching arm into disengaged position against the bias of the toggle spring and regardless of the maintenance of the handle in the "on" position, said one link being rigid with the operating handle and having a nose thereon engageable with the trigger for effecting return thereof to inoperative position when the handle is moved into "off" position after an automatic operation of the circuit breaker.
